Claims priority, application Netherlands May 8, 1957

5 Claims. (Cl. 328—72)

This invention relates to time switches comprising a controllable gas-filled or vapour-filled discharge tube fed via a resistor from a direct-current source and in which a charged capacitor is included as a negative biasing voltage in the grid circuit of the discharge tube, at least part of its period of discharge to the moment of ignition of the discharge tube being decisive for the desired period of time. Such a time switch may be used for several purposes, but is important more particularly for the control of two gas-filled or vapour-filled main discharge tubes connected in anti-parallel (either directly or through one or more auxiliary discharge tubes) for resistance welding.

According to the invention, a resistor is included between the junction of the cathode with the capacitor and the positive terminal and a switch is included between said junction and the negative terminal, the grid being connected to a tapping point, preferably adjustable, on a potentiometer included between the positive and the negative terminal.

The desired period of time is determined by the moment of the passage of current through the switch upon closure thereof and the moment when the discharge tube is ignited after the capacitor has sufficiently discharged.

Such a time switch may operate either synchronously or asynchronously with regard to the alternating supply voltage for the said main discharge tubes. In the former case, the switch between the cathode and the negative terminal may comprise a controllable discharge tube, the control of which is synchronized with said alternating voltage, whereas, in the second case, the switch may comprise a manually-operated mechanical switch or a relay.

According to a further feature of the invention, a resistor is included between the grid and the tapping point on the potentiometer, which resistor is preferably bridged by a rectifier, the anode of which is connected to the grid. The resistor serves as a discharge resistor for the capacitor, the presence of the rectifier permitting rapid recharging of the capacitor.

In order that the invention may be readily carried into effect, it will now be described more fully, by way of example, with reference to the accompanying drawing.

FIG. 1 shows a controllable gas-filled or vapour-filled discharge tube 1 having its anode connected via a resistor 2 to the positive terminal of a direct voltage source 3. The grid circuit of tube 1 includes a capacitor 4, of which the junction 5 with the cathode is connected via a resistor 6 to the positive terminal, on the one hand, and via a switch 7 to the negative terminal, on the other. The grid is also connected to a tapping point 8 on a potentiometer 9, included between the positive and the negative terminal 9, included between the positive and the negative terminal 9.

As soon as the direct voltage source 3 has been connected into circuit, the capacitor 4 with the switch 7 open will be charged via resistor 6 and the lower portion of potentiometer 9 to the voltage of the positive terminal decreased by the voltage on the tapping point 8, so that the grid of tube 1 has a negative biasing potential. The voltage at capacitor 4 is represented by 10 in FIG. 2, in which the positive and negative terminals are indicated by + and —. Furthermore, in FIG. 2, the positive voltage

2

at the anode is indicated by 11 and the voltage at the cathode of tube 1 is indicated by 12.

When switch 7 is closed point 13 at the cathode in FIG. 1 suddenly becomes negative due to the connection thereof to the negative terminal, so that the output terminal 14 also suddenly acquires a negative voltage. This is represented by the line 15 in FIG. 2. As a result thereof, the voltage at the grid of tube 1 suddenly becomes still more negative as represented by the line 16 in FIG. 2.

10 The tube 1 thus remains cut off. However, the capacitor 4 is now slowly discharged via the lower portion of potentiometer 9 and the switch 7, as represented by the line 17 in FIG. 2. At the moment 18, the capacitor has discharged to an extent such that tube 1 is ignited, as represented by the line 19. Consequently, the positive voltage at the anode of tube 1 decreases, for example, to the value 20, which is at the same time the voltage at the output terminal 21 in FIG. 1. Variations in potential thus occur at the terminals 14 and 21 with an interval as represented by the line 22 in FIG. 2, which variations may serve as control pulses for determining a desired period of time, for example the welding time for welding tools. The moment of ignition of tube 1 at 18 may be determined more accurately if peak voltages (for example from a saturated transformer) are superimposed on the voltage 17 of capacitor 4.

In the case described, the desired period of time is dependent upon the adjustment of the tapping point 8 on the potentiometer 9, by which the voltage 10 of capacitor 4 is determined, and upon the value of the lower portion of potentiometer 9, through which the capacitor is discharged, and hence also upon the adjustment of tapping point 8. This is objectionable in many cases. The disadvantage may be overcome by providing a separate resistor between the points 23 and 24 in FIG. 1, so that the time of discharge 22 is less dependent upon the adjustment of the tapping point 8.

It is frequently desirable that, immediately after expiration of the period of time 22, the circuit should again be ready for a subsequent switching manipulation. For this purpose, the capacitor 4 must first be re-charged. This takes up a certain time more particularly in the presence of a resistor between the points 23 and 24, which is usually comparatively high-ohmic as compared to the resistor 6 and the lower portion of potentiometer 9.

In order to overcome this disadvantage, the resistor 25 (see FIG. 3) between the points 23 and 24 may be bridged by a rectifier 26, the anode of which is connected to the grid, so that upon re-charging of capacitor 4, the resistor 25 is short-circuited and a rapid charge is thus rendered possible.

50 In certain cases, a plurality of switching manipulations in succession are desired without any interruption, for example with resistance-welding tools, for which a certain duration of the electrode pressure prior to welding, of the welding process and a certain duration of the electrode pressure after welding are desired.

In such cases, the switch 7 of FIG. 1 may be replaced by a time switch as represented by FIG. 4, in which identical parts are indicated by the same reference numerals and identical reference numerals of the second switch are primed. Between the output terminals 14', 14 and 21, there occur in this case variations in potential with relative time differences, which may serve, for example, for determining the duration of the electrode pressure and of the welding time, as indicated by 28 and 29 respectively in FIG. 5.

60 In a similar manner, the switch 7' of FIG. 4 may be replaced by a third time switch as shown in FIG. 1.

A simple automatic switch to replace the switch 7, 7' or the corresponding switch 7'' (not shown) in the said third time switch may be constituted by a flip-flop circuit

as shown in FIG. 6, it being possible for the whole circuit to be designed for only one work program or for repeated performance.

Instead of the switch 7", which is not shown, a gas-filled discharge tube 30 is arranged in flip-flop connection with a tube 31 by means of a common cathode resistor 32, a capacitor 33 and anode resistors 34 and 35. One output terminal 14" is connected to the anode of tube 30.

Tube 31, normally, is conducting, for example by means of an ignition pulse supplied at the arrow 36. The voltage at 14" on the anode of tube 30, which is cut off, is thus positive. If, now, tube 30 is ignited at 37, the voltage at 14" decreases and tube 31 extinguishes. The tube 1" is ignited after some time, subsequently tube 1' is ignited and then, also after some time, tube 1 is ignited. Due to the ignition of tube 1, a voltage pulse is supplied from the grid via a capacitor 38 to the grid of tube 31, resulting in this tube being ignited and tube 30 extinguishing. The initial condition is then restored again.

A control of the electrode pressure, the welding time and the after-pressure of the electrodes is indicated diagrammatically by 28, 29 and 39 in FIG. 7.

When a repetition of this program is desired, an output terminal 40 at the anode of tube 31 may be connected via a time delay 41 to the control of tube 30 so that a certain time after expiration of the pulse 21 in FIG. 7, the pulse 14" is again produced by ignition of tube 30.

What is claimed is:

1. A time switch circuit arrangement comprising an electron discharge device having an anode, a cathode and a control grid, means for supplying a direct voltage having a positive polarity terminal and a negative polarity terminal, a first resistor connecting said anode to said positive polarity terminal, a potentiometer connected between said positive and negative polarity terminals, said potentiometer having a tapping point thereon connected to said grid, a second resistor connected to said positive polarity terminal, a capacitor for applying a negative biasing potential to said grid connected in series between said second resistor and the said grid, means connecting a point in said series connection common to said second resistor and said capacitor to said cathode, a second electron discharge device having an anode, a cathode and a control grid, means connecting the anode of said second discharge device to said common point, a third resistor connecting the anode of said second discharge device to said positive polarity terminal, a second potentiometer connected between said positive and negative polarity terminals, said second potentiometer having a tapping point thereon connected to the grid of said second discharge device, a fourth resistor connected to said positive polarity terminal, a second capacitor for applying a negative biasing potential to the grid of said second discharge device connected in series between said fourth resistor and said grid of said second discharge device, means connecting a point in said series connection common to said fourth resistor and said second capacitor to the cathode of said second discharge device, switching means connected between said last-mentioned common point and said negative polarity terminal, means for deriving a first output voltage from said switching means, means for deriving a second output voltage from the anode of said second discharge device, means for deriving a third output voltage from the anode of said second discharge device, and means for deriving a fourth output voltage from the anode of said first-mentioned discharge device.

2. A time switch circuit arrangement comprising an electron discharge device having an anode, a cathode and a control grid, means for supplying a direct voltage having a positive polarity terminal and a negative polarity terminal, a first resistor connecting said anode to said positive polarity terminal, a potentiometer connected between said positive and negative polarity terminals, said second potentiometer having a tapping point thereon connected to the grid of said second discharge device, a fourth resistor connected to said positive polarity terminal, a second capacitor for applying a negative biasing potential to the grid of said second discharge device connected in series between said fourth resistor and said grid of said second discharge device, means connecting a point in said series connection common to said fourth resistor and said second capacitor to said cathode, a second electron discharge device having an anode, a cathode and a control grid, means connecting the anode of said second discharge device to said common point, a third resistor connecting the anode of said second discharge device to said positive polarity terminal, a second potentiometer connected between said positive and negative polarity terminals, said second potentiometer having a tapping point thereon connected to the grid of said second discharge device, a fourth resistor connected to said positive polarity terminal, a second capacitor for applying a negative biasing potential to the grid of said second discharge device connected in series between said fourth resistor and said grid of said second discharge device, means connecting a point in said series connection common to said fourth resistor and said second capacitor to the cathode of said second discharge device, switching means connected between said last-mentioned common point and said negative polarity terminal, means for deriving a first output voltage from said switching means, means for deriving a second output voltage from the anode of said second discharge device, and means for deriving a third output voltage from the anode of said second discharge device.

potentiometer having a tapping point thereon connected to said grid, a second resistor connected to said positive polarity terminal, a capacitor for applying a negative biasing potential to said grid connected in series between said second resistor and the said grid, means connecting a point in said series connection common to said second resistor and said capacitor to said cathode, a second electron discharge device having an anode, a cathode and a control grid, means connecting the anode of said second discharge device to said common point, a third resistor connecting the anode of said second discharge device to said positive polarity terminal, a second potentiometer connected between said positive and negative polarity terminals, said second potentiometer having a tapping point thereon connected to the grid of said second discharge device, a fourth resistor connected to said positive polarity terminal, a second capacitor for applying a negative biasing potential to the grid of said second discharge device connected in series between said fourth resistor and said grid of said second discharge device, means connecting a point in said series connection common to said fourth resistor and said second capacitor to the cathode of said second discharge device, a fifth resistor connecting the anode of said second discharge device to said last-mentioned common point, a fifth resistor connecting the anode of said third discharge device to said positive polarity terminal, a third potentiometer connected between said positive and negative polarity terminals, said third potentiometer having a tapping point thereon connected to the grid of said third discharge device, a sixth resistor connected to said positive polarity terminal, a third capacitor for applying a negative biasing potential to the grid of said third discharge device connected in series between said sixth resistor and said grid of said third discharge device, means connecting a point in said series connection common to said sixth resistor and said third capacitor to the cathode of said third discharge device, switching means connected between said last-mentioned common point and said negative polarity terminal, means for deriving a first output voltage from said switching means, means for deriving a second output voltage from the anode of said third discharge device, means for deriving a third output voltage from the anode of said second discharge device, and means for deriving a fourth output voltage from the anode of said first-mentioned discharge device.

3. A time switch circuit arrangement comprising an electron discharge device having an anode, a cathode and a control grid, means for supplying a direct voltage having a positive polarity terminal and a negative polarity terminal, a first resistor connecting said anode to said positive polarity terminal, a potentiometer connected between said positive and negative polarity terminals, said potentiometer having a tapping point thereon connected to said grid, a second resistor connected to said positive polarity terminal, a capacitor for applying a negative biasing potential to said grid connected in series between said second resistor and the said grid, means connecting a point in said series connection common to said second resistor and said capacitor to said cathode, a second electron discharge device having an anode, a cathode and a control grid, means connecting the anode of said second discharge device to said common point, a third resistor connecting the anode of said second discharge device to said positive polarity terminal, a second potentiometer connected between said positive and negative polarity terminals, said second potentiometer having a tapping point thereon connected to the grid of said second discharge device, a fourth resistor connected to said positive polarity terminal, a second capacitor for applying a negative biasing potential to the grid of said second discharge device connected in series between said fourth resistor and said grid of said second discharge device, means connecting a point in said series connection common to said fourth resistor and said second capacitor to the cathode of said second discharge device, switching means connected between said last-mentioned common point and said negative polarity terminal, means for deriving a first output voltage from said switching means, means for deriving a second output voltage from the anode of said second discharge device, and means for deriving a third output voltage from the anode of said second discharge device.

4. A time switch circuit arrangement comprising an electron discharge device having an anode, a cathode and a control grid, means for supplying a direct voltage having a positive polarity terminal and a negative polarity terminal, a first resistor connecting said anode to said positive polarity terminal, a potentiometer connected between said positive and negative polarity terminals, said second potentiometer having a tapping point thereon connected to the grid of said second discharge device, a fourth resistor connected to said positive polarity terminal, a second capacitor for applying a negative biasing potential to the grid of said second discharge device connected in series between said fourth resistor and said grid of said second discharge device, means connecting a point in said series connection common to said fourth resistor and said second capacitor to said cathode, a second electron discharge device having an anode, a cathode and a control grid, means connecting the anode of said second discharge device to said common point, a third resistor connecting the anode of said second discharge device to said positive polarity terminal, a second potentiometer connected between said positive and negative polarity terminals, said second potentiometer having a tapping point thereon connected to the grid of said second discharge device, a fourth resistor connected to said positive polarity terminal, a second capacitor for applying a negative biasing potential to the grid of said second discharge device connected in series between said fourth resistor and said grid of said second discharge device, means connecting a point in said series connection common to said fourth resistor and said second capacitor to the cathode of said second discharge device, switching means connected between said last-mentioned common point and said negative polarity terminal, means for deriving a first output voltage from said switching means, means for deriving a second output voltage from the anode of said second discharge device, and means for deriving a third output voltage from the anode of said second discharge device.

mon to said fourth resistor and said second capacitor to the cathode of said second discharge device, a third electron discharge device having an anode, a cathode and a control grid, means connecting the anode of said third discharge device to said last-mentioned common point, a fifth resistor connecting the anode of said third discharge device to said positive polarity terminal, a third potentiometer connecting between said positive and negative polarity terminals, said third potentiometer having a tapping point thereon connected to the grid of said third discharge device, a sixth resistor connected to said positive polarity terminal, a third capacitor for applying a negative biasing potential to the grid of said third discharge device connected in series between said sixth resistor and said grid of said third discharge device, means connecting a point in said series connection common to said sixth resistor and said third capacitor to the cathode of said third discharge device, switching means connected between said last-mentioned common point and said negative polarity terminal, said switching means comprising fourth and fifth electron discharge devices each having an anode, a cathode and a control grid connected in flip-flop circuit arrangement with each other, means connecting the anode of said fourth discharge device to the cathode of said third discharge device and means connecting the grid of said fifth discharge device to the grid of said first-mentioned discharge device, means for deriving a first output voltage from said switching means, means for deriving a second output voltage from the anode of said third discharge device, means for deriving a third output voltage from the anode of said second discharge device, and means for deriving a fourth output voltage from the anode of said first-mentioned discharge device.

4. A time switch circuit arrangement comprising an electron discharge device having an anode, a cathode and a control grid, means for supplying a direct voltage having a positive polarity terminal and a negative polarity terminal, a first resistor connecting said anode to said positive polarity terminal, a potentiometer connected between said positive and negative polarity terminals, said potentiometer having a tapping point thereon connected to said grid, a second resistor connected to said positive polarity terminal, a capacitor for applying a negative biasing potential to said grid connected in series between said second resistor and the said grid, means connecting a point in said series connection common to said second resistor and said capacitor to said cathode, a second electron discharge device having an anode, a cathode and a control grid, means connecting the anode of said second discharge device to said common point, a third resistor connecting the anode of said second discharge device to said positive polarity terminal, a second potentiometer connected between said positive and negative polarity terminals, said second potentiometer having a tapping point thereon connected to the grid of said second discharge device, a fourth resistor connected to said positive polarity terminal, a second capacitor for applying a negative biasing potential to the grid of said second discharge device connected in series between said fourth resistor and said grid of said second discharge device, means connecting a point in said series connection common to said fourth resistor and said second capacitor to the cathode of said second discharge device, a third electron discharge device having an anode, a cathode and a control grid, means connecting the anode

5 of said third discharge device to said last-mentioned common point, a fifth resistor connecting the anode of said third discharge device to said positive polarity terminal, a third potentiometer connected between said positive and negative polarity terminals, said third potentiometer having a tapping point thereon connected to the grid of said third discharge device, a sixth resistor connected to said positive polarity terminal, a third capacitor for applying a negative biasing potential to the grid of said third discharge device connected in series between said sixth resistor and said grid of said third discharge device, means connecting a point in said series connection common to said sixth resistor and said third capacitor to the cathode of said third discharge device, switching means connected between said last-mentioned common point and said negative polarity terminal, said switching means comprising fourth and fifth electron discharge devices each having an anode, a cathode and a control grid connected in flip-flop circuit arrangement with each other, a delay circuit, means coupling the anode of said fifth discharge device to the grid of said fourth discharge device, means connecting the anode of said fourth discharge device to the cathode of said third discharge device and means connecting the grid of said fifth discharge device to the grid of said first-mentioned discharge device, means for deriving a first output voltage from said switching means, means for deriving a second output voltage from the anode of said third discharge device, means for deriving a third output voltage from the anode of said second discharge device, and means for deriving a fourth output voltage from the anode of said first-mentioned discharge device.

5. A time switch circuit arrangement comprising an electron discharge device having an anode, a cathode and a control grid, means for supplying a direct voltage having a positive polarity terminal and a negative polarity terminal, an impedance element connecting said anode to said positive polarity terminal, a first resistor element, a potentiometer connected between said positive and negative terminals and comprising a second resistor element, a third resistor element, a unidirectionally conducting device shunted across said third resistor element, means for applying a negative biasing potential to said grid maintaining said discharge device at anode current cutoff for a predetermined time interval, said means comprising a capacitor having one terminal thereof connected to said positive terminal through said first resistor element and having the second terminal thereof connected to said negative terminal through said second and third resistor elements connected in series, means for connecting the junction of said capacitor and said third resistor element to said control grid, and switching means connected between said negative terminal and the junction of said capacitor and said first resistor element, said capacitor and the second and third resistor elements having values at which the capacitor discharge time is substantially equal to said predetermined time interval.
